SYNCHRONIZED OIL LEVEL CONTROL

James A. Rook and Clay H. Rook, East Palestine, Ohio

Application May 15, 1934, Serial No. 725,814

6 Claims. (Cl. 137—68)

This invention relates to oil burners and the object of the invention is to provide a synchronized constant oil level control for such burners.

In oil burners of the stove and range type, 5 wherein oil is fed to the burner from a tank such as inverted metal tank or bottle, difficulty has always been experienced in providing an even feed to the burners and a constant oil level in the oil bowl and vaporizing unit and oil channels 10 of the burners.

In devices for feeding oil to the burners now in present use, there are fluctuations in the level of the oil in the oil bowl and vaporizing unit which produce an irregular flame and consequent 15 heating effect. The oil is fed from the tank through a comparatively large opening in the tank cap which is closed by a spring pressed plunger valve. When the tank is placed in its inverted position on the oil bowl, the plunger 20 engages an abutment which opens the tank valve, the oil flowing out of the opening and the air entering through the same opening. When the opening is sealed by the rising of the oil in the oil bowl, no air can enter the tank and therefore 25 the flow of oil ceases. The oil in the vaporizing unit and oil channels is gradually consumed and the flame dies down as the oil level sinks. When the opening in the tank is sufficiently uncovered by this lowering of the oil level in the oil bowl, 30 air can enter the tank so that flow of oil to the bowl and vaporizing unit will be resumed.

The opening in the tank through which the oil and air pass in this well known construction is relatively large so that the oil will feed very 35 rapidly when it is uncovered and atmospheric pressure exists in the tank and thus the flame will flare up when air is admitted to the tank to feed the oil. Tests have shown that, in this type of tank feed, the oil will feed from 50 to 150 40 drops per minute and that there will be an average interval of 10 $\frac{1}{4}$ minutes between regurgitations, resulting in an oil level variation at times of 7/64" of more than .105". It is only necessary to observe a burner fed by a device of this 45 well known type to become cognizant of the disadvantages of such irregular feeding of the oil, among which may be mentioned the fact that it takes from 10 to 20 minutes to saturate the wicks. During operation, the flame flares 50 up and dies down and the heat consequently fluctuates.

Another difficulty experienced in such burners fed from inverted tanks is that of preventing overflow of the oil when the burner is shut off. 55 If the tank is left in its inverted position and

there should be a rise in temperature, the air in the tank will expand and force some of the oil out; upon a lowering of the temperature, the air will contract and more air will be drawn into the reservoir. It is obvious therefore that a subsequent rise in temperature will force more oil out of the tank and that these fluctuations of temperature will result in flooding the oil bowl and vaporizing unit with a consequent dangerous overflow. It is also to be noted that there is 10 danger of oil leakage and accidental discharge while placing the tank in position in the oil bowl or removing it for replenishing the oil.

It is the object of our invention to overcome 15 these disadvantages by providing a constant level feed wherein the oil will be fed only a few drops at a time and the time between regurgitations will be only a few seconds, with oil level variations less than .001", thereby ensuring an even 20 regular heating flame. The device also comprises 25 a positive means for shutting off the flow of oil entirely when the burner is turned off thereby preventing overflow, as well as preventing leakage or accidental discharge when replenishing oil supply.

We accomplish the above and other objects of the invention, which will be apparent as the description proceeds, by means of the device shown in the accompanying drawing, in which

Fig. 1 is a vertical sectional view of a conventional oil reservoir or bowl for a burner of the range type showing an inverted bottle tank provided with our constant level control device;

Fig. 2 is a sectional view looking into the interior of the control device with the flow shut off 35 in open position;

Fig. 3 is a view similar to Fig. 2 with the flow shut off in operative position;

Fig. 4 is a top plan view of the device constituting our invention, the tank neck on which 40 it is positioned being shown in section;

Fig. 5 is a vertical section through the device, partly broken away, showing the oil and air feed openings and the flow shut off; and

Fig. 6 is a bottom plan view of the device constituting our invention.

On the drawing, in which like reference characters indicate like parts on all the views thereof, 1 indicates the conventional form of reservoir or bowl for range oil burners, and 2 indicates the oil supply tank here shown as of the inverted bottle type. 3 indicates our constant level control device which is here shown in the form of a casing detachably connected to the inverted bottle tank.

The main bottom wall of the casing 3 is provided with an opening 4 having a sloping peripheral wall terminating in a knife edge whereby the periphery of the opening on the interior of the casing is relatively larger than the periphery on the exterior, the sloping wall serving to direct the flow of the oil. The casing is formed with a thickened circumferential wall 5 having an extension projecting downwardly therefrom below the main bottom wall and forming a continuation thereof in which is formed a passage 7, which terminates on the interior of the casing in close proximity to the opening 4, as clearly shown in Figs. 2 and 5. The opening 4 and the passage 7 are located so closely to each other that they are in effect a single opening for the passage of oil out of the tank when it is first placed in inverted position.

Our improved shut off for the flow of liquid comprises a valve cap 8 of such size that it will cover both the opening 4 and the passage 7. The valve cap is provided with a recess 9 in which is loosely seated one terminal of a valve stem 10 of inverted U-shaped formation, the operating 25 spring for the valve cap being indicated at 11. The other terminal of the stem is mounted in and secured to the extension 6 by any suitable means such as the nut 12 or by riveting or peening. The loose mounting of the valve cap ensures that the valve will always positively close the opening and passage when in its operative position.

It has been found that this form of valve stem or plunger is particularly effective for the purpose for which it is designed, since it holds the valve firmly to its seat and yet is easily operable to uncover the opening and passage. A handle 13 is provided for operating the valve which is housed within a cutaway portion 14 so as not to interfere with the seating of the tank bottle and casing in the conventional type of reservoir or oil bowl. By so locating the handle in the cutaway portion, the danger of accidentally operating the valve is eliminated. A recess 15 is provided in the casing wall for the reception of the valve cap when in inoperative position.

A baffle is secured by soldering or otherwise to the interior of the casing and serves to close off the interior and prevent inspection thereof or removal of the parts therein unless the baffle is removed or destroyed in which case it would be apparent that the device had been tampered with.

In operation, the valve is first closed and the tank placed in proper inverted position in the reservoir or bowl. The valve is then opened so that the oil flows momentarily through both the opening 4 and the passage 7 to the bowl or vaporizing unit. As soon as the pressure in the tank falls below atmospheric, and the level of the oil sinks below the bottom of the casing, air will enter through the opening 4 and permit the flow of oil. When the oil reaches the level 65 of the bottom of the casing, or slightly thereabove, when, due to the fact that the flow of air to the top of the tank is shut off, the flow of oil ceases. The burner being lighted, the oil in the bowl will be drawn off and the oil level will sink 70 but not over .001".

As will be apparent, the exterior atmospheric pressure bearing against this thin film of oil will tend to force it inwardly from the periphery of the casing toward the opening 4 so that air 75 may pass into the tank. It is to be noted that

the opening 4 is off center so the air pressure will be directed mainly from a point in the film radially toward the center of the casing. When the air pressure reaches a point where it may penetrate the film an air bubble, such as is shown at 5 C, will detach itself and enter the tank through the opening 4.

As is obvious, the bubble will become enlarged as it passes into the tank, due to the fact that the pressure on the exterior of the bubble is less than atmospheric in the tank, so that it will be of such size that it appears to cover both the opening 4 and the entrance to the passage 7 thus cutting off the tendency of the oil to flow through the passageway 7. As the oil discharges 15 a slight vacuum will be formed at the entrance to the passageway, thus holding the oil in the passageway and forming an obstacle to the flow of oil therethrough. Thus, it is apparent, the oil will flow more readily out of the opening 4. 20 When the oil starts to flow out of 4 entrance of air into the tank is prevented and therefore the flow of oil will be extremely limited, only a few drops at a time.

It is also to be noted that the flow of oil 25 through the passageway 7 is retarded and prevented because of the friction encountered in the walls of the passageway, while the flow is facilitated through the opening 4 due to the fact that its walls are tapered and the interior diameter is greater than the diameter of the passageway. Another feature which enters into the operation of the device is the fact that the lower end of the passageway 7 is always submerged 30 in the oil in the bowl which acts as a cushion or balancer preventing the ready flow of the oil therethrough.

It will thus be seen that we have provided a device in which the oil will feed evenly to the vaporizing unit, the regurgitations occurring frequently and depositing only a few drops at a time. It is likewise apparent that we have provided a synchronized constant oil level control for stoves and ranges of the oil burning type and for similar devices wherein it is desirable to 45 maintain a constant liquid level control which is simple in construction and effective in operation.

While we have described our invention in connection with oil burners, it is obvious that it is 50 adapted for use in connection with any liquid feeding device where it is desired to maintain a constant liquid level, and it is thought unnecessary to enumerate the many uses to which it may be put.

Having thus described our invention, what we claim as new and desire to secure by Letters Patent is:—

1. In a constant liquid level control device, a casing, the bottom wall of the casing having two openings therethrough the entrances to which are in the same plane, and a valve closure for said openings, said closure having a U-shaped stem one end of which is secured to the bottom wall of the casing and the other end loosely mounted in said closure, said closure and said stem being within the casing.

2. In a constant liquid level control device, the combination of a casing having a bottom wall with two closely adjacent openings therethrough, a closure for said openings located on the interior of the casing, and a handle located on the exterior of said casing for operating said closure, said casing having a cut-away portion in which said handle is movable.

3. In a constant liquid level control device, a casing, an extension projecting downwardly below the bottom wall of said casing, said extension having an opening therethrough, the bottom wall of said casing having two closely adjacent openings therethrough, one of said openings forming a continuation of the opening in the extension, said first named opening being of the same diameter throughout and said second named opening having a tapered peripheral wall terminating in a knife edge at the outer surface of the bottom wall.

4. In a constant liquid level control device, a casing having a main bottom wall provided with two relatively small, closely adjacent openings therethrough, the entrances to the openings being in the upper plane of the main bottom wall, a valve closure for said openings, a stem for said valve closure, said stem being U-shaped, with one end secured to said casing and the other loosely mounted in said closure, and a coiled spring surrounding said stem and bearing against said closure to hold the closure over said openings.

25 5. In a constant liquid level control device, a

casing having a main bottom wall provided with two closely adjacent openings therethrough, the entrances to the two openings being in the plane of the interior surface of said bottom wall, a passageway leading from one of said openings and extending below the main bottom wall of the casing, the other of said openings terminating in the exterior surface of said bottom wall and having an inwardly flaring conical wall, said entrances being substantially tangent to each other.

6. In a constant liquid level control device, a casing having a main bottom wall provided with two relatively small openings therethrough the entrances to which are in the plane of the interior surface of said bottom wall, the adjacent points of the peripheries of said entrances being separated by a narrow space, a passageway leading from one of said openings and extending below the main bottom wall of the casing, the other of said openings having an inwardly flaring conical wall and being located off center of the central vertical axis of the casing.
